THERMIONIC TUBE

Henry W. Parker, Toronto, Ontario, Canada, assignor to Rogers Radio Tubes, Limited, Toronto, Ontario, Canada, a corporation of Ontario, Canada

Application February 16, 1932, Serial No. 593,219

4 Claims. (Cl. 250—27.5)

My invention pertains to thermionic tubes and relates in particular to thermionic tubes of the so-called screen grid type.

One of the principal objects of my invention comprises producing a screen grid tube of simplified construction.

A further object comprises producing an efficient screen grid tube of simplified construction.

A still further object comprises producing a construction for screen grid tubes which, while retaining the same desirable electrical characteristics of such tubes now in use, can be fabricated in mass production more easily and cheaply.

I accomplish the above desirable features and others which will be hereinafter pointed out and discussed by providing metallic shields or ferrules at the upper and lower extremities of the inner screen electrode cooperating with an outer screen electrode which is attached to the outer surface of the glass envelope of the tube to provide effective screening.

In the drawing accompanying and forming a part of this specification, I have illustrated a partially sectioned elevation of my improved screen grid tube.

Referring now particularly to the drawing, my improved tube comprises the usual glass envelope 1, cemented in the usual base 2. A stem 3 supports the usual anode 20 by means of standards 18 and 19, one of which, 19, serves as the terminal therefor. The cathode 12, preferably of the indirect heated type, is provided with the usual heater terminals and cathode terminal as shown in the drawing. The control grid adjacent to the cathode is formed preferably of a helix of wire wound on supports 10 and 11 and connected by means of conductor 6 with the control grid contact 5. The inner screen grid in my improved construction may be in the form of a metallic mesh but is preferably formed of a helix of wire wound on supports 16 and 17 and attached to the upper extremity of these supports by spot-welding or otherwise I provide a metallic shield or ferrule 7. To the lower extremity of the screen grid supports 16 and 17, I provide a shouldered shield or ferrule 15 which is attached to the supports 16 and 17 preferably by spot-welding. The shoulder of shield or ferrule 15 supports a disk or washer 14 of mica or other refractory insulating material which serves to support the standards 10 and 11 which, in turn, support the control grid helix. The upper extremity of both the cathode 12 and control grid supports pass through openings provided in a disk or washer 13 of mica or other refractory insulating material which

serves to maintain the electrodes in their proper relative positions. The entire assembly of inner screen grid, control grid, and cathode, just described, is spot-welded to supports 8 and 9 held in the press 3.

One of these supports as 8 serves as a terminal and is connected by conductor 24 with the contact prong 25, thus providing electrical contact for the inner screen grid. The outer screen 4 consists of metal, preferably zinc, sprayed or otherwise applied on the outer surface of the envelope 1 and covers practically the outer surface of the envelope exposed above the base except for a portion near the top where sufficient space is left to provide the necessary insulation 10 resistance between the control grid contact 5 and the metallic coating 4. This metallic coating serves as the outer screen usually placed within the envelope 1 and adjacent to the anode 20. This outer screen may be, if desired, connected 15 by means of a conductor 22 with conductor 21, serving as a terminal for the cathode 12 and both conductors connected to contact prong 23 in the base of the tube, although such connection is not necessary as the coating 4 may be connected to 20 ground in other ways.

In mass production utilizing automatic exhaust machines it is desirable to provide a slot or opening 27 in the anode 20 bridged by a wire conductor 26 in the form of a hair pin, the extremities of 30 which are preferably spot-welded to the anode, to allow the radio frequency currents used in heating up the electrodes of the tube in the exhaust process to quickly penetrate to the inner grids and ferrules that these elements of the tube may be 35 readily heated to redness during the exhaust process. The hair pin conductor 26 acts as a high resistance bridge across the slot in the anode and reduces the heat of the anode sufficiently to allow the grids and ferrules to quickly reach the desired 40 temperature without unduly heating the anode.

Screen grid tubes now in use employ invariably an inner screen between the control grid and the anode and an outer screen adjacent the anode 45 but within the glass envelope of the tube and both of these screens are electrically united with a top screen or cover entirely covering the upper part of the anode, in order that the control grid lead or terminal may be shielded.

I have found by experiment that my simplified 50 construction produces exactly the same degree of shielding as the usual type just referred to and yet that a tube constructed in accordance with my invention evidences the same desirable low capacitance between the control grid and the anode 55

as that in the usual tube and that the electrical characteristics are in other respects practically identical.

It will be observed that as the entire inner screen, control grid and cathode may be constructed in the form of a sub-assembly and introduced as such in the final assembly of the tube in the press merely by spot-welding to the standards provided therefor in the press, that the construction in mass production is greatly simplified and consequently cheapened. It will be further observed that all of the electrodes in the sub-assembly can be definitely fixed with respect to their relation and that the sub-assembly can be fabricated in quantity and held in stock without deterioration or change in relative position of the electrodes until desired for complete assembly of the tube, a feature obviously advantageous in mass production.

I have found by experiment that the metal shields or ferrules 7 and 15 when provided in the relative positions shown in the drawing cooperate with the exterior screen 4 to function in exactly the same manner as the screens now used in such tubes and that therefore my simplified construction while producing a tube which may be more easily and cheaply constructed in mass production performs exactly similar to similar tubes now in use.

Having thus completely described my invention, what I claim as new and desire to secure by Letters Patent of the United States is as follows:

1. A thermionic tube comprising, an enclosing envelope, a press within said envelope, a screen grid comprising a pair of metallic ferrules and a metallic mesh therebetween supported by said press, a control grid supported by said screen grid, a cathode within said control grid, an anode

supported by said press and partially surrounding said screen grid, the opening in said anode being bridged by a conductor, the electrical resistance of which is much higher than the electrical resistance of said anode.

2. A thermionic tube comprising, an enclosing envelope, a press within said envelope, a screen grid comprising a pair of metallic ferrules and a metallic mesh therebetween supported by said press, a control grid within said screen grid, a 10 cathode within said control grid and an anode, a portion of which consists of a conductor having a higher electrical resistance than the remaining portion surrounding said screen grid and supported by said press.

3. A thermionic tube comprising, an enclosing envelope, a press within said envelope, a pair of standards supported by said press, said standards supporting a screen grid in the form of a pair of standards having a wire helix on the mid- 20 portion and a metallic ferrule on each extremity thereof, a control grid within said screen grid and supported thereby, a cathode within said control grid and an anode without said screen grid and supported by said press, said anode being provided with a slot bridged by a conductor in the form of a looped wire.

4. A thermionic tube comprising, an enclosing envelope, a press within said envelope, a pair of standards supported by said press, said standards 30 supporting a screen grid in the form of a pair of standards having a wire helix on the mid-portion and a metallic ferrule on each extremity thereof, a control grid within said screen grid, a cathode within said control grid and an anode without 35 said screen grid and supported by said press, said anode being provided with a slot bridged by a conductor in the form of a looped wire.

HENRY. W. PARKER.
